(57) **CLAIM**

The ornamental design for a mouthpiece mouth prop, as shown and described.

DESCRIPTION

FIG. 1 is a perspective view of a mouthpiece mouth prop showing our new design.

FIG. 2 is a back view thereof.

FIG. 3 is a front view thereof.

FIG. 4 is a right side view thereof, with the left side view being a mirror image thereof.

FIG. 5 is a top view thereof; and,

FIG. 6 is a bottom view thereof.

The broken lines shown in the Figures show portions of the mouthpiece mouth prop that form no part of the claimed design. The broken lines immediately adjacent the shaded areas represent the bounds of the claimed design.

The shade lines in the Figures show contour and do not claim surface ornamentation or treatment.
